METHOD AND APPARATUS FOR MOLDING
CONCRETE PIPE

Charles B. Breedlove, Detroit, Mich.

Application May 26, 1938, Serial No. 210,240

3 Claims. (Cl. 25—32)

This invention relates in general to a method and apparatus for forming concrete piping, and it is particularly related to the formation of monolithic or seamless piping to be used in sewer and other work employing concrete piping.

One of the main objects of this invention is to provide an improved concrete pipe-forming process whereby the piping is formed and laid simultaneously without the otherwise necessary handling thereof.

Another object of the invention is to improve the art of forming concrete piping so that the formation process is continuous from start to finish throughout the entire length of the pipe, the resulting pipe being monolithic and seamless, and the process of the forming thereof at the same time accomplishing the laying thereof.

Another object of the invention is to employ the same pressure which is used for introducing the wet concrete into the forms for the piping to remove said forms from those portions of piping which have initially set, said pressure in moving said forms at the same time increasing the density of the concrete in said piping.

Another object herein is to provide improved apparatus for use in the above novel process for the accomplishment of the above objects.

Other objects and advantages will become readily apparent from a reference to the following specification taken in conjunction with the accompanying drawings, of which there are two (2) sheets and in which:

Figure 1 shows the pipe forming apparatus in position for accomplishing the first step in the continuous process of simultaneously forming and laying the formed pipe;

Fig. 2 shows the apparatus and pipe during an advanced step of the process;

Fig. 3 shows the apparatus and pipe at the final stage of forming and laying of the latter, and

Figs. 4 and 5 are transverse sections through the pipe and apparatus in cases where the process is to be performed on open-cut or tunnel work, respectively.

There is shown in Figs. 1 through 4 a pre-cut trench 10 with a form 12 disposed therein and solely supported thereby. Form 12 is shown in cylindrical cross section, but such specific showing is for the purpose of illustration only. Internally disposed within the form 12 is an inner form or pilot, generally indicated at 14, the form 14 being held at one end in proper spaced relation to form 12 by means of an annular cap 55

member 16 which is secured thereat to both of said forms, the proper spacing between said forms and along their lengths as the concrete is forced between the forms being attained by the use of a spacing member 18 which is slideable between the forms 12 and 14 in close fitting relation thereto and ahead of the concrete by the pressure of the concrete.

The inner form or pilot 14 is preferably made up of a plurality of separately attachable and removable sections 20, joined together by bolts or other means, and made individual for the purpose of acquiring the proper length of the assembled form 14. It is to be noted that the length of form 14 is shown as approximately double that of form 12, the purpose of which to be explained later. Any conventional type of supporting means 22 for the free end of form 14 may be used, its use being optional but many times preferable, especially for inner forms of great length.

The outer form 12 is provided near its forward end with an inlet 24 into which concrete 26 is forced under high pressure by the pumping apparatus, generally indicated at 28. Apparatus 28 can be of any known type as long as it is capable of producing pressures high enough for the accomplishment of the desired results. In open-cut work, such as in Figs. 1 through 4, apparatus 28 may either be supported on the form 12 as shown, or it may be supported on the bank 10 and in communication with inlet 24 by means of a flexible supply conduit (not shown). In tunnel work, such as in Fig. 5, apparatus 128, similar to apparatus 28, is mounted on the inside of the inner form 114, similar to inner form 14 except for the provision in the form 114 of the inlet 124, the tunnel and outer form in Fig. 5 being represented, respectively, by the numerals 110 and 112.

Since the invention contemplates the application of end thrust at the initially-set end of the concrete, namely, at the free end of the outer form 12, such as is shown in Fig. 2, so that subsequent pressure on the concrete applied at the inlet 24 will cause the forms 12 and 14 to move away from that end of the concrete which has initially set, such as is shown in Fig. 3, the trench 10 is presumed to have been cut out so as to accommodate the extra sections 20 of inner form 14. The end of the trench 10, indicated at 30, will then serve as an abutment for the jacks or other thrust reacting members, generally and diagrammatically indicated at 32. It is neces-

sary to have the trench 10 longer than the outer form 12, but it need only be long enough to accommodate a single extra section 20, any that need be added later as the inner form is drawn away from the set end of the pipe can be added as needed. Also, instead of the jacks 32 there can be employed a system of vertical piling (not shown), said piling being driven into the ground up against the end of the spacing member 18 and the circumference of the inner form 14 so that the thrust of form 14 will be properly taken up by said piling. Other thrust reacting means may be employed and the invention contemplations that same are available for use.

When the apparatus, including the outer and inner forms 12 and 14, the bulk-head and spacing members 16 and 18, and the pumping apparatus 28, have been assembled as shown in Fig. 1, concrete 26 is forced under high pressure through the inlet 24. The longitudinal speed of travel of the forms 12 and 14 governs the lengths thereof necessary to insure proper hardening of the concrete in the piping formed thereby, and it also governs the amount of hydraulic pressure required; in other words, said necessary form length is directly proportional to said chosen form speed, and said required pressure is also directly proportional to said chosen form speed. The concrete entering the annular space between the forms 12 and 14 is forced through and along this space, as shown in Fig. 2, until it reaches the free end of the outer form 12, the spacing member 18 being movable ahead of the concrete and properly spacing during its travel the forms 12 and 14 one from the other, and said forms remaining stationary during this step of the process.

When or before the concrete reaches the free end of the form 12, the jacks 32 or other suitable thrust reacting means are placed in position, as shown in Fig. 2, the thrust reaction thus set up causing a pressure to be built up by the pumping apparatus sufficient to move the two forms 12 and 14 as a unit away from the thrust supported end of the concrete pipe. The movement of the two forms 12 and 14 by the pressure of the incoming concrete continues until the pipe is formed in desired length, said length comprising the portions lying without and within the two forms 12 and 14. The supply of concrete is then shut off, but the motion of the two forms is continued in the same direction and at the same rate of speed as before by the pumping apparatus, jacks or other means, so that the pipe throughout its entire length will have been confined between the two forms for a uniform time.

From the above discussion and description it will be seen that the pipe forming process provides a uniformly set pipe when it, as in Fig. 3, is freed by both forms 12 and 14. The two forms support the concrete during the length of time it takes the incoming concrete to reach the end of the outer form, and the inner form, being substantially double the length of the outer form, continues to support the pipe internally for the additional length of time it takes the free end of the inner form to traverse the portion of the pipe uncovered by the outer form. The pressure exerted on the concrete against the thrust reaction of the jacks 32 increases the density of the concrete. And, the formed pipe is made seamless and monolithic, the process is continuous from start to finish, and the pipe is laid as it is formed, all because of the inherent nature

of this novel process. Increasing the density of the concrete enables the thickness of the pipe in any case to be materially cut down.

Concrete of normal consistency to be used for sewer work of normal dimensions becomes initially set after approximately five hours. Therefore, the inner form is of such a length as to have internally supported each particle of concrete being left unsupported thereby for said five hours. Practice has proved that the concrete need be externally supported for a period of approximately between two and three hours, and the length of the outer form is, therefore, made accordingly.

The disclosure in Fig. 5 shows the adaptation of the described novel method of and apparatus for forming and laying piping to tunnel work, as distinguished from open-cut work, the only differences being that the wet concrete is introduced into the forms through the inner form rather than through the outer form, the outer form is made shorter than the open-cut outer form so that the concrete will leave the outer form while still not initially set and of such consistency as to fill the void between the earthen tunnel wall and the inner form, the inner form is made shorter than the open-cut inner form because the form speed in tunnel work is much slower than the form speed in open-cut work for the same size pipe, and the pumping apparatus is carried by the inner form rather than by the outer form or by the bank, as in open-cut work. This method and apparatus used in tunnel work is an important time saver, there being no stoppage during the forming and laying process, as in brick tunnelling, and there being no need for relining the formed tunnel, as in block tunnelling with shields. In brick tunnelling, the sand hogs dig while the brick masons must idly wait, and vice versa; in the above novel method, the sand hogs dig while the concrete pipe is being formed and laid. In block tunnelling with shields, the entire inner wall of the tunnel must be relined with a thick facing in order to seal the block seams; in the above novel method, the piping is continuous, seamless and monolithic. Also, another important advantage in the above novel method is the complete absence of rehandling of materials.

Although the invention has been described in some detail such description is not intended to limit the scope of the inventive idea. The right is reserved to make such changes in the specification as will come within the purview of the attached claims.

What I claim is:

1. The method of simultaneously forming and laying concrete pipe for tunnel purposes which comprises, concentrically positioning a pair of annular forms so that their common axis is substantially coincident with the axis of the desired pipe and the annulus between which forms is cross sectionally dimensioned similarly as the pipe and has a closed end, introducing wet concrete under pressure into the annulus from within the inner form along a continuously unrestricted path of travel so that the concrete is free to move longitudinally through the annulus toward the end thereof opposite said closed end exclusively under the influence of said pressure, and terminating the travel of the concrete toward said opposite end when the concrete thereat is in a position corresponding to the position selected to be occupied by one end of the pipe, whereupon the reaction set up by said closed end

and the immobile concrete when concrete introduction and pressure application are continued effectuates movement of the forms away from said one end of the pipe toward the position selected for the other end of the pipe.

2. In an apparatus for simultaneously forming and laying concrete pipe for tunnel purposes and comprising, a pair of concentrically disposed forms defining an elongated annulus having a cross section similar to that of the pipe to be formed and an axis capable of being arranged substantially coincident with the axis desired for the pipe, a closure member carried by said forms over the head end of said annulus, means providing a source of wet concrete, means providing a source of pressure applicable to said concrete for bodily moving the latter, and concrete flow inlet means formed in and carried by the inner form of said pair and providing from within said inner form an unrestricted communication between said annulus and said moving concrete so that concrete entering said annulus under the influence of said pressure is thereafter conveyed for a predetermined period of form immobility through said annulus toward the end thereof opposite said closure carrying end exclusively responsive to said pressure and thereafter against said closure member to protract said forms relatively to said concrete.

3. In an apparatus for simultaneously forming and laying concrete pipe for tunnel purposes and comprising, a pair of concentrically disposed forms defining an elongated annulus having a cross section similar to that of the pipe to be formed and an axis capable of being arranged substantially coincident with the axis desired for the pipe, a closure member carried by said forms over the head end of said annulus, means providing a source of wet concrete, means carried within the inner form of said pair and providing a source of pressure in active communication with said concrete for bodily moving the latter, and concrete flow inlet means formed in and carried by said inner form and providing from within said inner form an unrestricted communication between said annulus and said moving concrete so that concrete entering said annulus under the influence of said pressure is thereafter conveyed for a predetermined period of form immobility through said annulus toward the end thereof opposite said closure carrying end exclusively responsive to said pressure and thereafter against said closure member to protract said forms relatively to said concrete.
